(57) **CLAIM**

The ornamental design for a watchcase, as shown and described.

DESCRIPTION

FIG. 1 is a front perspective view of a watchcase showing my new design;

FIG. 2 is a front elevational view thereof;

FIG. 3 is a left side devotional view thereof;

FIG. 4 is a right side elevational view thereof;

FIG. 5 is a rear elevational view thereof;

FIG. 6 is a top plan view thereof; the bottom plan view is a mirror image of the top plan view; and,

FIG. 7 is a rear perspective view thereof.

The dashed broken lines in the drawings show portions of the watchcase that form no part of the claimed design, and the dash-dot-dash broken lines in the drawings illustrate the boundary of the claimed design.

1 Claim, 5 Drawing Sheets
